DISPLAY STAND

Edward Mackasek, Ellwood City, Pa.

Application November 2, 1932, Serial No. 640,817

3 Claims. (Cl. 240—2)

This invention relates to the merchandizing of particular commodities; and consists in an article of commerce, a display stand, adapted to receive and sustain the commodity—in the intended instance, bottles of motor oil for automobiles—and to present it attractively to the purchasing public.

In the accompanying drawing Fig. I is a view in perspective of the display stand of the invention, free of its load. Figs. II and III are views to smaller scale; Fig. II is a view of the stand in plan from above, and in partially laden condition; Fig. III is a view in vertical section, on the plane indicated by the line III—III, Fig. II.

The stand is of general box-like form, preferably rectangular, and open above. It is conveniently formed of three endless rectangular belts 1, 2, and 3, of angle iron, of four legs 4 of angle iron, united to the belt 3, and of end walls 5, side walls 6, and bottom wall 7, of sheet metal, united together and to the belts of angle iron, thus integrating the whole. The means of union are, conveniently, bolts 8; and, when such means are employed, the stand manifestly may be packed and shipped in knocked-down condition, and assembled when it is to be used. The end and side walls may be cut away as indicated at 50 and 60, both to afford more elegant appearance and to avoid a battered and disfigured lower edge.

The side walls 6 have opposite medial upward extensions 61, to the upper edges of which the belt 1 is united.

It will be particularly remarked that there are three belts 1, 2, and 3; that one flange of the angle of each belt is vertically disposed, to which vertically disposed flanges the side and end walls of sheet metal are secured; that the other flange of the angle of each belt is horizontally disposed; that to the horizontal flange of the belt 3 the bottom wall is secured; that the horizontal flanges of the belts 1 and 2 afford seats within the rim of the open upper end of the stand—one such seat (formed by the flange of belt 1) being at the upper edges of the extensions 61 of the side walls, and the other seats (formed by the flanges of belt 2) being at the upper edges of the side and end walls, and just below the bases of the extensions 61.

Glass bottles B filled with motor oil, a translucent substance, (the commodity for which the stand is primarily intended) are assembled in baskets 9 formed of reticulated wire; and the baskets, equipped with handles 90, are so proportioned as to be applicable to and removable from seats afforded by the angle irons. The

baskets are light-penetrable: the flood of light passing through their interstices suffices. The assembly is clearly illustrated in Figs. II and III. Within the stand structure provision is made for illumination. A partition wall 70 of inverted V-shape is formed of sheet metal and secured to the floor 7. This structure extends medially throughout the length of the stand. It affords support for the sockets of electric lamps L; it constitutes a conduit through which electric wiring W may be carried and within which such wiring may be protected; and its upper surfaces constitute reflecting surfaces which direct the light upwardly and outwardly.

Interiorly the sheet-metal walls and floor of the stand and the outer surface of the partition 70 are rendered light-reflecting in high degree, conveniently by covering them with coatings of white enamel; and exteriorly the walls may have legible characters 62, 63, these outer surfaces so embellished being also, preferably enameled. Legible characters are formed in the side or end walls or both, by perforation, to the end that, when the stand is illuminated from within, such characters may be read. These characters formed in the side walls by perforation may correspond to the characters formed upon the walls by exterior decoration, as is indicated by the white dots upon the shaded field of the characters 62. When the lamps within the stand are lit and external light is reduced, the stand becomes a transparency, and the characters so formed by perforation become clearly legible.

The translucent bottles of oil B within the containers 9 in place upon the stand, are illuminated with light from the lamps L. Thus at night the stand becomes an attractive display stand: the clarity and color of the oil thus conspicuously displayed are beautiful and attractive, while the illuminated legend on the side walls of the stand affords the necessary information, such as the nature of the commodity, the brand, the name or trade-mark of the producer, and the like.

The stand illustrated in the drawing is adapted to carry three oblong baskets 9, each holding a dozen bottles of oil, and, by virtue of the upward extensions 61 of the side walls and the elevated situation of the belt 1 of angle iron, the middle basket of the three, with its load, is raised above the other two. In consequence, the whole, when illuminated, affords a greater and more effective display.

I claim as my invention:

1. A display stand for a translucent commodity

including side walls, end walls, and bottom wall of opaque sheet metal, integrated upon horizontally arranged belts of rectangular shape, formed of angle iron, with vertically-extending flanges against which the side and end walls are secured and horizontally-extending flanges, upon one of which the bottom wall is secured, a light-penetrable container for the commodity to be displayed applicable to and removable from a seat provided for it in the otherwise open upper end of the stand by the horizontally-extending flanges of one of said belts, one of the sheet-metal walls of said stand bearing a legible character formed in it by perforation, illuminating means arranged within the stand, the sheet-metal walls of the stand being provided interiorly with a light-reflecting enamel coating.

2. A display stand for a translucent commodity including rectangular side walls, end walls, and bottom wall of opaque sheet metal, the opposite side walls being provided at their upper edges with medially positioned rectangular extensions, the said walls being integrated upon three horizontally-arranged belts of rectangular shape formed of angle iron, arranged one at the base of the side and end walls, one at the upper edges of the side and end walls and the third at the upper edges of the extensions of the side walls, the said belts of angle iron including vertical flanges to which the side and end walls are se-

cured and horizontal flanges to which, in the case of the lowest belt the bottom wall is secured, and which, in the other cases, afford seats, three light-penetrable containers for the commodity to be displayed, removable and replaceable upon such seats, an inverted V-shaped partition of sheet metal secured to the bottom wall within, and extending on medial line longitudinally of the stand, sockets for electric lamps set in the opposite slopes of such partition, one of the walls of said stand being perforated to form a legible character, and the interior sheet-metal surfaces of the stand being provided with a light-reflecting enamel coating.

3. A display stand for a translucent commodity including side walls, end walls, and bottom wall of sheet metal, integrated upon horizontally arranged belts of rectangular shape, formed of angle iron, with vertically extending flanges against which the side and end walls are secured and horizontally extending flanges upon one of which the bottom wall is secured, a light-penetrable container for the commodity to be displayed applicable to and removable from a seat provided for it in the otherwise open upper end of the stand by the horizontally extending flanges of one of said belts, and illuminating means arranged within the stand.

EDWARD MACKASEK. 30
